UNITED STATES PATENT OFFICE.

CHARLES T. CROCKER, OF FITCHBURG, MASSACHUSETTS.

SOAKING MACHINE EMPLOYED IN MAKING PAPER.

Application filed November 30, 1927. Serial No. 236,700.

My invention relates to the art of paper making, particularly to that branch of it, wherewith waste paper stock is treated with a chemical solution, for the purpose of cutting or removing ink or the like from the surface of the paper; said invention residing in a machine for the treatment of a continuous stream of pieces of waste paper with said chemical solution, and consisting of 5 mechanical improvements in the soaking machine illustrated and described in U. S. Letters Patent for improvements in the art of paper making, No. 1,326,849, granted to me December 30, 1919.

15 In the use of this old soaking machine, pieces of metal, such as nuts, washers, wire binders, eyelets, pins and other hard substances become separated from the saturated pieces of paper, settle upon the perforated bottom, catch in the perforations of the false bottom, and remain there until manually removed by rake or shovel, an operation requiring the non-use of the machine for about 20 one day each week.

25 With the old machine, the action of the paper, mechanically moved from the inlet-end of the machine by duckers, to the discharge-end of the machine, causes the liquid chemical to flow with it, and tends to raise 30 the level of the liquid in the discharge-end of the machine, and to lower it at the inlet-end; the equalization of these levels of this liquid being brought about by the flow of the liquid seeking its own-level, through the 35 perforated bottom of the machine.

In my improved machine, hereinafter described, I have provided, in place of the perforated bottom, a solid cast bottom upon which these pieces of metal cannot catch, but 40 which necessitates means whereby the liquid level at the discharge-end of the machine, and the low liquid level at the inlet-end of the machine, may become substantially equalized. This is accomplished by the substitution of what I call open-duckers, for 45 some of the old solid duckers; the action of the open-duckers, so far as the movement of the paper forward through the machine is concerned, remains the same, the revolving 50 fingers or vanes pushing the paper down and forward, while the parts of the open-duckers allow the liquid chemical to flow back therethrough, and seek and find its own level.

In short, the main objects of my improvements over the old type of machine are:

First, to provide a soaking machine that, instead of collecting and removing the metal pieces from the soaking paper stock, will carry said pieces along with said soaking stock, and deliver the same directly to a 60 screen or a washing machine, say that described in U. S. Letters Patent No. 1,474,893, and issued November 20, 1923, to Bigelow Crocker, wherein said particles of dirt and pieces of metal may be removed from the 65 soaked paperstock, thus doing away with the manual removal of said particles, required by the old soaking machines.

Second, to give the duckers such form and arrangement, that most of the liquid in the 70 receptacle will be allowed to maintain a normal level without being pumped through a pipe from the delivering end of the receptacle to the entering end.

In the drawings illustrating the principle 75 of my invention, and the best mode now known to me of embodying the same in operative structure, to attain the objects to said invention,

Figs. 1 and 2 show said structure in elevation, two sheets of drawings being required for the purpose, and

Fig. 3 is a longitudinal section of the same; all of these figures being somewhat diagrammatic, for the sake of simplicity and 85 clearness.

This apparatus may, in general terms, be said to comprise a receptacle or tank 1 for the reception of a suitable chemical liquid 2; means 3 for feeding paper stock 4 and 90 any affixed pieces of metal, into the tank; devices 5 and 6 for submerging said pieces of paper and metal, and conveying the same through the liquor; some of said devices 5 permitting the level of the liquid to remain 95 substantially the same both in front of, and behind said devices; mechanism 7 for draining and delivering said paper and said metal pieces to a pipe leading to a washing machine, and means 8 for reclaiming the liquor. 100

The papers 4, with any pieces of metal there may be affixed thereto, to be treated, are thrown on to a continuous feed-apron 3, moving over suitable rolls 9, which are operating in a manner well understood, and require no further description; the delivery end of the feed-apron being over the receiving end 10 of the receptacle 1.

Here are located the submerging devices or duckers 5, for completely immersing the 110

pieces of paper delivered by the feed-apron, and moving them along the solid bottom to the propelling devices 6. These submerging devices consist of a series of six cylinders 11, 12, 13, 14, 15, 16, the first of which 11 receives its power by means of gears 17, 18, operated by a pulley 19 and a belt 20, driven by a main pulley 21, and shaft 22 above the receptacle. A chain 23 transmits 10 the motion of rotation from the first to the other cylinders by means of idle sprocket wheels 24 connected with the cylinders 11 to 16 inclusive. The main sprocket wheels vary in size, as indicated, hence the cylinders 16 rotate at obviously different speeds.

Each of the first two cylinders 11 and 12 comprises a shaft 26 and a plurality of abutting hubs 27 secured to the shaft, and having rearwardly curved vanes 28 for forcing the paper down into the liquor, the bearings being arranged along the top of the receptacle in such a position that the ends of the curved vanes project down almost to the imperforate bottom 29; and the abutting 20 hubs 27 being partially immersed in the liquor, so that every piece of paper falling into the tank cannot pass by either of these 25 two cylinders 11 and 12, without first being submerged into the liquor.

30 The remaining four cylinders 13, 14, 15 and 16, differ in structure from the first two just described, only in the fact that the hubs are separated from each other, and allow the liquor to move between them, in 35 its attempt to stand at the same level on either side of each cylinder, whereas with the first two the liquor has to pass under the hubs rather than between them.

I have found that the number and arrangement of the vanes indicated in the 40 drawings operate successfully.

The papers 4 supplied, as above stated, from the feed-apron 3, fall on to the first cylinder 11, the rotation of which forces 45 each piece of paper down through the liquor and on to the solid bottom 29, and forward into position to be acted upon by the vanes of the next succeeding cylinder 12. These 50 vanes then engage the papers, and positively force each piece under the surface of the liquor so that each piece is thoroughly immersed more than once, before it reaches the remaining submerging devices 13, 14, 15 and 16, it being noted also that these radial 55 vanes push forward the mass of papers as well as the liquor in which they are immersed, the level of the liquor in front of each of the two cylinders 11 and 12 being a little higher than that behind.

60 It is at this stage of the process that pieces of metal affixed to the pieces of waste paper begin to become separated from the saturated papers, by the agitation brought about by the vanes; the metal pieces collecting under the submerging cylinders on

the imperforate bottom, but being forced and carried along with the mass of saturated pieces of paper.

From these two submerging cylinders 11 and 12, the papers and metal pieces are 70 taken by the remaining cylinders 13, 14, 15 and 16, and likewise pushed forward along the solid bottom to the propelling mechanism 6. The chemical liquor, due to the open type construction of the new duckers 75 13, 14, 15 and 16, is allowed to flow back over the top of the submerged papers, to the inlet end of the machine, through the separated hubs of the duckers.

The propelling mechanism 6 comprises a 80 rake 30 supported upon uprights 31 on the top of the receptacle. These uprights are provided with shafts 32 having weighted arms 33 with depending links 34, to which the rake 30 is pivotally connected through 85 shafts 35 transverse the rake. These arms 33 are connected by a horizontal rod 36 so that there may be a parallel motion for raising and lowering one end of the rake in accordance with the motion of the other end. 90 To move the rake longitudinally, the following mechanism is used: power is transmitted by the main power shaft 22 and the belt 37 through a pulley 38 having a gear 39 meshing with a gear 40, on which is an eccentric 41 supporting a roller 42 that, in turn, is on a supporting bar 43, one end portion being pivoted to the rake, while the other end portion is slotted vertically by the reception of a crank pin 44 on the gear wheel 40. The roller and eccentric are thus adapted to raise and lower the rake. To move it longitudinally, a connecting rod 45 is provided and pivotally connected to the rake and to the supporting bar 43. Obviously by means of the eccentric and the crank, the connecting mechanism will cause the entire rake and teeth to have an elliptical motion for submerging and moving the pieces of paper, while they are submerged, forward through the liquor and along the solid bottom of the receptacle.

From the propelling mechanism 6, the saturated paper and all foreign matter mixed with them, are seized by a vibrating doffer rake 46, for the purpose of delivering them to a discharge pipe 47 leading to a washing machine (not shown). This rake is operated by a crank shaft 48, the frame 49 of the rake being extended and forming a cam surface 50 to move over a roller 51 on a support 52 fixed to a standard 53.

Extending upwardly from the imperforate bottom 29 and over the depression 54 at the delivery end 55 of the tank, is an inclined imperforate surface 56 and a perforated surface 57 along which the teeth of the rake are adapted to work; the cam surface, the position of the roller, and the length of the tank, 125

all being so designed that the teeth may take the desired path parallel with the inclined perforated bottom, during the upward and outward movement of the rake, and a horizontal, rearward, and downward motion during the return of the rake.

Across one row of the teeth, there is a wooden blade 58, the bottom edge of which lies just above the plane of the roller teeth. 10 I find that this prevents any possible damage being done by the teeth accidentally engaging the upwardly inclined surface of the perforated bottom. The power to rotate the crank shaft 59 is derived through a train of 15 gears, 60, 61, 40, driven by gear 39.

It will be seen that the teeth of the rake thus hoe the saturated pieces of paper, and the pieces of foreign matter, up and over the upwardly inclined imperforate and 20 perforate surfaces 56, 57, the liquid chemical draining off through the latter into a separate depression 54, as shown, thence flowing through an overflow 62 to a pipe 63 and a pump 64, to be returned with any 25 excess overflow through the overflow 65 to the receiving end of the tank. The stock at this point flows over a lip 66, into a receptacle 67, where fresh water is added through a pipe 68, so that it will freely 30 flow through pipe 47, and on to a washing apparatus below, but not shown, and forming no part of my invention.

The chemical liquor may be supplied through feed-pipes, as 69.

35 To drain the liquor from the main receptacle, when necessary, an outlet plate 70, removably secured in the side of the tank, is provided, and, when removed, allows the liquor to flow out and drop into a drain 40 71 beneath the tank.

The principal objects of my invention have now been obtained, namely, the avoidance of the necessity of manual removal of pins, clips, fasteners and other metallic objects which cling to the perforated bottom, this foreign material now being passed 45 along with the soaking papers; and the maintenance of a substantially uniform level of the chemical liquid in the soaking tank, by allowing the liquor to move quite freely from the delivery-end to the entering-end of the receptacle.

Having described the structure and operation of my invention and desiring to protect 50 my invention in the broadest manner legally possible, what I claim is:—

1. In a soaking machine, a tank having an imperforate bottom, to hold a chemical liquor; a series of duckers to completely 55 immerse, in said liquor, paper stock at the receiving end of the tank, and move the

stock along the bottom; other duckers, to move said stock further along said bottom, said duckers being formed to allow the liquor in the tank to find and keep its own level; 60 means to rotate all of said duckers.

2. In a soaking machine, a tank having an imperforate bottom, to hold a chemical liquor; a series of duckers to completely 65 immerse, in said liquor, paper stock at the receiving end of the tank, and move the stock along the bottom; other duckers, to move said stock further along said bottom, said duckers being formed to allow the liquor in the tank to find and keep its own 70 level; means to rotate all of said duckers; and means to withdraw and drain said stock from said tank, and deliver the same for the purpose of washing.

3. In a soaking machine, a tank having 75 an imperforate bottom, to hold a chemical liquor; a series of duckers to completely immerse, in said liquor, paper stock at the receiving end of the tank, and move the stock along the bottom; other duckers, to 80 move said stock further along said bottom, said duckers being formed to allow the liquor in the tank to find and keep its own level; means to rotate all of said duckers; 85 means to withdraw and drain said stock from said tank, and deliver the same for the purpose of washing; and means to spray said stock with fresh water while being 90 delivered from said machine.

4. In a soaking machine, a tank having 95 an imperforate bottom, to hold a chemical liquor; a series of duckers to completely immerse, in said liquor, paper stock at the receiving end of the tank, and move the stock along the bottom; other duckers, to 100 move said stock further along said bottom, said duckers being formed to allow the liquor in the tank to find and keep its own level; means to rotate all of said duckers; 105 a drain tank; means to withdraw and drain said stock from said tank, and deliver the same for the purpose of washing; overflows from said tank, and drain tank, to receive excess of chemical liquor from said tanks; and a pump to force said excess into 110 the receiving end of the tank.

5. In a soaking machine for paper stock, a soaking tank; a ducker, to move paper stock along the bottom of the soaking tank, allow the liquor, which is pushed ahead of 115 the stock by the ducker, to flow back through the ducker, and maintain a substantially uniform level, both in front and behind the ducker, and means to rotate the ducker.

In testimony whereto I hereunto affix my 120 signature.

CHARLES T. CROCKER.
